Wiley, both of Marion, Ind.

Application September 9, 1940, Serial No. 355,968

7 Claims. (Cl. 18—56)

This invention relates to a method of fabricating liquid repellent and heat resistant structures such as relatively deep seamless containers, and the like, from sheet material of pulp character and the additional products or ingredients associated with or incorporated in such sheet material.

Articles which may be so fabricated are of various forms.

This invention is a continuation-in-part of the invention disclosed in the copending application Serial No. 288,343, filed August 4, 1939, and entitled, "Sheet pulp container forming process and apparatus therefor," and the present invention is directed primarily to the process and product.

In the before mentioned application, there is disclosed one method of impregnating prime sheet pulp material of bleached or unbleached character fed from rolls to the impregnating and moistening mechanisms and then fed therefrom to apparatus for severing blanks from the sheet material for subsequent formation of the several blanks into article formation.

The present invention may utilize stock of this character or may utilize stock wherein the impregnating materials are initially incorporated in the sheet at the time the pulp is formed into a sheet. Such latter stock merely requires moistening to the desired degree.

The process may be practiced, if desired, at the "dry" end of the paper sheet forming machine, in which event, the sheet is not dried to the extent required for shipment but only to that required for operation in this invention. The invention disclosed herein, therefore, is capable of being applied to the end of a paper sheet making machine providing the stock from that machine has incorporated therein the proper materials and is of the proper moisture content, or the paper sheet from a standard machine may be fed to the impregnating mechanisms disclosed in the before mentioned application.

Either form of preliminary production may be utilized or any suitable form of preliminary production may be utilized, all without departing from the scope of the present invention.

The present invention contemplates operating upon pulp material of sheet form which is sufficiently moist to make the stock pliable without cracking and which stock has incorporated therein or applied to the surface suitable sizing or resin material, including the necessary solvent or solvents, so that the finished product will be heat resistant and liquid repellent, and under certain instances may have sufficient dielectric strength rendering same suitable for electrical insulation purposes.

The present invention broadly is disclosed in the before mentioned application and copending continuation-in-part thereof, and for that reason

to provide a proper understanding of the present invention, Figs. 2 to 7, inclusive, of the aforesaid application Serial No. 288,343, disclosure appear herein as Figs. 1 to 6, inclusive. Inasmuch as the invention is primarily directed to a process and not to the specific apparatus illustrated herein by way of example only, and is directed to the product or material utilized, but brief reference herein will be had to the specific apparatus disclosure duplicated by way of drawing illustration.

The full nature of the present invention will be understood from the accompanying drawings and the following description and claims.

In the drawings,

15 Fig. 1 is a vertical, sectional view through an embodiment representing the blanking and initial forming portions of the apparatus, the intermediate turret and associated portions of the apparatus wherein the initial form of the article is obtained, and the conveyor structure for removing the initially formed articles for subsequent treatment.

20 Fig. 2 is a vertical sectional view of the last mentioned conveyor structure, the initial drier structure and a second conveyor arrangement adapted to receive the initially formed articles following initial and "free" drying when discharged from the first conveyor.

25 Fig. 3 is a central sectional view through one form of finishing press and the second mentioned associated conveyor, the latter being operatively associated with the press for semi-final formation of the article and a second drier arrangement.

30 Fig. 4 illustrates the second mentioned conveyor arrangement, the discharge end of the second mentioned drier, an article discharging means and an article receiving structure, by way of example only, inasmuch as the specific form of the present invention contemplates interposing, between the discharge of the second mentioned drier and the article discharging means, a final finishing press arrangement similar to that illustrated in Fig. 3.

35 Fig. 5 is an enlarged plan view of two separable pairs of forms carried by the rotatable turret shown in Fig. 1, one pair being shown in open position and the other in the closed position. While illustrated herein as in a common plane at 90° apart, it is to be understood they are faced to planes 90° apart.

40 Fig. 6 is a plan view of a sheet with areas for present blanking purposes and openings formed by previous blankings suitably illustrated therein.

45 In order that a more complete understanding of the process, the primary subject matter of this invention, may be obtained, certain explanations will be incorporated in the following description of the previously referred to apparatus illustrated by Figs. 1 to 6, inclusive, which is suitable for 50 performing said process.

Inasmuch as the present illustrations are duplications of a portion of that illustrated, described and claimed in detail in the before mentioned copending application, Serial No. 288,343, of which this application is a continuation-in-part, the description of the apparatus illustrated herein will be but briefly set forth.

Referring to Fig. 1 it will be noted there is a festoon arranged, properly treated pulp sheet F which passes over the roller 57 and thence over the roller 58 and is fed between the guides 60. The waste passes between the members 83 and discharges to the container 86, being reduced in size by means of the choppers 85. Between the guides 60 and the elements 83, the sheet has an intermittent movement in timed relation to machine operation. The initial movement following one operation is to advance the sheet the desired amount so as to present new areas from which additional blanks may be cut—see Fig. 6. These blanks are cut while the sheet is stationary. The blanks, while the sheet is stationary, are forced through openings in the dies 64 supported by structure 62 shown in Fig. 1, and by plungers 65.

It will be understood there are two tiers of these die openings and associated therewith are two tiers of plungers 65 carried by the crosshead 74. The blanking mechanism is carried by the crosshead 68. Thus, the blanking mechanism makes initial contact with the sheet for blank formation and then the crosshead 74 is advanced to draw the blanks thus formed through the confronting creasing structures 66 and 67 by pushing centrally on each blank. The blanks thus partially formed, then are caused by plungers 65 to pass through dies 64 and to seat in the external molds 92 shown in Fig. 5 in the lower left hand corner. These molds are carried by a turret 87—see Fig. 1—which has intermittent and herein rotational movement.

Following the seating of the blanks in partial formation in the molds 92 positioned as shown in Fig. 5 and in the left hand portion of Fig. 1, reference being had to the turret, the plungers 65 are retracted to the position shown in Fig. 1 and the blanking die structure 68 is retracted as shown in Fig. 1. When these dies are free of the sheet, sheet movement is effected for the presentation of new areas for blanking and forming and during this feeding movement of the sheet, the turret is indexed 90°, as shown in Fig. 1. The sheet waste passes to receptacle 86 as described.

In the turret indexing movement, the mold divided structure shown in the lower left hand portion of Fig. 5 is assembled as shown in the upper right hand portion of Fig. 5. This is illustrated at station K in Fig. 1. In juxtaposition to these then linearly aligned molds 92, there is provided a dual crosshead arrangement, one of which is of neck ring character and the other of which is of plunger character, there being as many neck rings and plungers as there are now linearly aligned mold cavities.

During the movement of the blanking die 68 to the right in Fig. 1, the neck ring 110 advances to the mold 92 at station K and engages the partially formed article and the mold. During the advancing movement of the plunger 65 in Fig. 1, the plunger 111 in Fig. 1 similarly is advanced. The retraction movements are similarly timed.

During the sheet advancing interval, the turret then moves the assembled and linearly aligned molds and included articles from station K to station L. Herein the single crosshead 117 carry-

ing the forming plunger 118 is advanced during plunger advance at other stations to semi-complete the article. Retraction of the crosshead 117 and plunger 118 is correspondingly timed. 5 During the next sheet advancing movement, the turret 87 again indexes the previously mentioned mold structure to station M where the articles are discharged from molds 92.

A conveyor structure 127 carrying mushroom-like supports—see Fig. 1—is associated with elevating and lowering mechanism, illustrated as of swinging arm type and cam operable, so that when the articles are ejected from the molds 92 by means such as indicated at 125, the articles are supported by the then elevated mushroom-like supports 128—129—130 carried by conveyor 127, see dotted lines, Fig. 2. Then when the conveyor is lowered for mold clearance, see full lines Fig. 1, the articles and mushroom-like supports are free of the molds. Upon subsequent operation, the turret 87 indexes from station M to initial station J and in that indexing movement, the mold arrangements separate from the closed arrangement shown in the upper part of Fig. 5 to the open arrangement shown in the lower part of said figure, thus completing the mold cycle upon the turret.

Reference now will be had to Fig. 2. Therein there is illustrated a drier oven having the housing portion 140, adjustably controlled overhead vent arrangements 148—149, overhead baffle 146, and adjustably controlled heat supply arrangements, 143—144—145 at the bottom thereof. The conveyor 127 has its upper run entering the housing through the opening 141 and thence passes upwardly to the top of the oven. In the oven the conveyor passes to and fro below the baffle as illustrated. Just above the plane of entrance to the conveyor, the conveyor passes out through an opposite opening 142 and is there associated with an article retainer arrangement 162 which holds the articles on the mushroom supports until the mushroom supports are inverted. This member 162 is the cause of the inversion of said mushroom supports because the same are so supported that they always maintain, except at this portion of their travel, a predetermined and vertical position.

This discharge arrangement also is oscillatable and cam operable—see 168 and 167—so that the article, if of cup formation, may be discharged positively from the mushroom supports by means 236—237, if desired, and be received by a combination receiver and mold 164 carried by the conveyor arrangement 165. The lower run of the mushroom supporting conveyor 127 from the discharge station N passes into the opening 142, thence, through the lower portion of the oven 140 and out through the opening 141 and back to the oscillatable support at station M—see Fig. 1. The conveyor 165 from the station N—see Fig. 2—passes under the roller 173 and over the roller 176 and into the opening 177 of a semi-finishing press structure 178, the molds 164 riding on an adjustable bed plate 179 of that press.

This press is shown most clearly in Fig. 3 and it includes, if desired, a first and second stage formation structure, one of which may be a plunger without a neck ring and the other which may be a plunger with a neck ring, both plungers having simultaneous movement and the neck ring having predetermined timed movement, the same operating in timed relation with the plungers shown in Fig. 1, because the conveyors have timed movement relative thereto. It is to be under-

stood the conveyors and sheet move when the plungers and neck rings are stationary and vice versa.

At this station O—see Fig. 3—semifinishing of the article is effected. Thereafter the conveyor 165 passes out of the opening 181 of the semifinishing press 178 and enters through opening 197 into the second drying oven having controlled overhead vent arrangements 204—205, an overhead baffle 203 and a controlled heat supply near the bottom as indicated by 200—201—202.

The conveyor 165 with its molds 164 passes to and fro from the upper end of the oven toward the bottom thereof, the articles during the inverted runs of said conveyor being retained in the molds 164 by suitable guide and retainer arrangements illustrated in said Figs. 3 and 4, and indicated by the numeral 209, see Fig. 4.

The conveyor 165 passes out of the second oven 196 through opening 210, see Fig. 4. The return portion of the conveyor enters said opening 210, passes through the oven 196 and passes outwardly therefrom through opening 218 immediately below entrance opening 197 and thence passes—see Fig. 3—below the press shown in Fig. 3 and to the receiving station shown in Fig. 2 and indicated by the letter N.

Reference now will be had to Fig. 4. In Fig. 4 there is shown a discharge arrangement at station Q. However, as set forth in the copending application and as hereinafter specified in the preferred specific form of the invention, there is interposed between the discharge 210 and station Q another and finishing press arrangement substantially similar to that illustrated in the left hand portion of Fig. 3 and herein the final finishing is effected by said second press. The conveyor 165 after discharging from such a second finishing press may enter a third oven, if desired, or may pass directly to the discharge station Q. The articles then may be discharged from molds 165 into a suitable container 227 or as set forth in the aforementioned application, Serial No. 288,343, the articles may be discharged to other conveyor mechanism for other treatment, such as ornamentation in addition to formation.

Having thus briefly described one form of apparatus suitable for practicing the present process, one primary subject matter of the present invention, reference now will be had to the latter.

From the foregoing it will be understood the blank of pulp material suitably coated or impregnated or initially formed with certain ingredients included therein is successively formed into article formation at the various stations in connection with the turret arrangement. There is considerable moisture content present during this formation. Some of this moisture by reason of and in the initial formation of the article is mechanically extruded from the stock being deformed. The article then is passed through the first oven which is at a temperature sufficient to remove considerable excess moisture not mechanically removed heretofore. This temperature is insufficient to cause thermal reaction between the ingredients applied to the sheet or with which the sheet has been impregnated or which has been included in the sheet in its initial formation. The articles supported on these mushroom-like elements of the first conveyor arrangement permit the articles to be subjected to what may be termed "free" drying in this first oven. "Free" drying may be defined as substan-

tially drying at will while unconfined but merely supported for transfer purposes.

After being "free" dried the articles are subjected to a pressing operation which further mechanically consolidates the pulp and the addition products included therein or applied thereto and also mechanically distributes the surface exposed portions of the latter to a greater degree and compacts the product to the desired rigidity, size and shape.

This first oven in effect evaporates the moisture carrying agent, usually water, as well as the solvent of the solution containing the ingredients other than the pulp. These may be resins or products of similar character or may be sizing materials. This evaporation or "free" drying usually leaves small granular parts of the solids, such as the resin et cetera, between and on the fibers of the pulp. The second oven operating at a much higher temperature causes the size or resin materials to melt or flux and flow, thus insuring substantially complete surface coating upon the interior of the article more especially, although such coating on the exterior of the article is similarly melted and flowed. There thus results a substantially complete surface coating of the article and the article then may be discharged to a receiver as shown in Fig. 4.

In many cases, however, it is preferable to interpose between the discharge station Q—see Fig. 4—and the second oven shown in the same figure, a final finishing press similar to that shown in the left hand portion of Fig. 3 and this press applies pressure to the article for consolidating the melted or fluxed size or resin on the surface of the article and consolidates the pulp body into its finished form, producing a product that is relatively rigid and which has a very smooth finish and which is heat resistant and liquid repellent and in special instances is of electrical insulation character. In many instances the second finishing press, when provided, is not required to be utilized.

Substantially all stock folding or fluting markings are entirely eliminated in the first finishing press.

By the judicious use of included ingredients, such articles in addition may be provided with high dielectric strength and thus be available for electric insulation purposes. In other words, an article of this character may constitute an insulation type housing or container for electrical equipment, such as a wall switch and the like, by way of example only.

It is to be understood the second oven does not completely remove all the water from the stock. Usually what is commercially known as dry articles contain approximately 5% or 6% of moisture, and if desired, the finished products may contain that amount of moisture.

It also is to be understood that whenever and wherever desired, the plungers may be of resilient character or may be of metal character and in either event, the same may be heated by electrical heating elements included therein. Since the last mentioned is merely supplemental to the present invention and since heating dies or plungers, and/or molds per se are old in the art of paper receptacle fabrication same are not herein illustrated.

The present invention, therefore, is broadly directed to a method of forming molded, liquid repellent and heat resistant structures from sheet pulp material which has had incorporated therein or which has been impregnated or coated with

suitable ingredients, such as size or resin materials, chiefly workable through the instrumentality of water as a conveying and distributing medium.

Essentially, the steps of the process consist in forming from a blank an article while the blank is wet, to the desired degree, then "free" drying the same without affecting the ingredients last mentioned, and to evaporate excess moisture and ingredient solvent not theretofore mechanically extruded or separated therefrom, then semi-finishing or final finishing the article, the first drying being insufficient to cause reaction of the ingredients with reference to the pulp and then the final heating or drying expelling the remainder of the moisture to the extent noted (commercial dryness) together with any and all other solvents, the ingredients associated with the pulp melting and flowing to form a finished surface or coating of the character described, and whenever and wherever desired or required, such an article thus formed may be further subjected to the final pressure consolidation or ironing and finishing step with or without the application of heat.

While the invention has been illustrated and described in great detail in the drawings and foregoing description, the same is to be considered as illustrative and not restrictive in character.

The several modifications described herein as well as others which will readily suggest themselves to persons skilled in this art, all are considered to be within the broad scope of the invention, reference being had to the appended claims.

The invention claimed is:

1. The process of forming molded, liquid repellent and heat resistant structures of a shape other than a flat sheet including molding a flat blank of paper pulp sheet to substantial container structure form, the sheet including coating material of size, resin or like character and liquid solvent such as water, et cetera, such molding mechanically modifying the sheet to the approximate final shape of the structure and simultaneously expressing a certain portion of the liquid from the structure, then free drying the structure to expel additional liquid from the structure and at a temperature insufficient to thermally react upon the coating material, then pressure forming the structure into final form and compacting the coating material upon the structure, and then heating the final formed structure to a temperature sufficient to expel additional liquid to produce a commercially dry structure and to melt and flow the coating material upon the surface of the structure to form a continuous and homogeneous coating of liquid repellent and heat resistant character upon the structure.

2. In the process of forming dished molded, liquid repellent and heat resistant container structures, the steps of heating a partially molded unconfined dished structure initially formed from a solvent sized, flat, moist pulp sheet, such heating being at a temperature sufficient to partially set the form of the structure and simultaneously expel a certain portion of the sizing solvent and moisture from the structure but insufficient to thermally affect the sizing, then pressing the partially dried and set in confined dished structure to smooth the structure into final form and simultaneously distribute the surface exposed size over the structure surface, and then heating the structure to an appreciably higher temperature sufficient to remove additional moisture and siz-

ing solvent to produce a commercially dry structure and to melt and flow the surface distributed size for substantially completely surface coating of the dished structure.

3. In the art of forming molded structures of relatively deep cavity type and from flat suitably moistened blanks of paper sheet pulp including size and the like including forming the structure by a plurality of successive pressure applications upon the blank, such formation including initial formation of pleating in the structure side wall by pressure to the blank central portion and subsequent stock deformation and distribution by centrally and laterally applied pressure to eliminate evidence of the pleating, then free drying the pressure formed structure at a temperature insufficient to cause thermal reaction of the size, then drying at a temperature sufficient to cause thermal reaction of the size to melt, flux and flow same upon the structure surface, but insufficient to scorch the latter, and then pressure forming the size coated structure to final form.

4. In the art of forming molded dished structures from flat sheet moist paper pulp including size and the like, the formation from flat sheet to dished structure form, subjection of the formed structure to two successive heats, the first heating in duration and temperature being insufficient to thermally effect the size and the like but sufficient for partially drying the formed non-flat structure to the desired degree, the second heating in duration and temperature being sufficient to "melt" and "flow" the size over the structure surface and to further dry the structure but insufficient to scorch the same, and then pressure ironing and consolidating the formed pulp body and "melted" surface following the second heating.

5. In the art of forming molded dished structures from flat sheet moist paper pulp including size and the like, the formation from flat sheet to dished structure form, subjection of the formed structure to two successive heats, the first heating in duration and temperature being insufficient to thermally effect the size and the like but sufficient for partially drying the formed non-flat structure to the desired degree, the second heating in duration and temperature being sufficient to "melt" and "flow" the size over the structure surface and to further dry the structure but insufficient to scorch the same, and by compacting by pressure the structure body size and the like between the heatings.

6. In the art of forming molded dished structures from flat sheet moist paper pulp including size and the like, the formation from flat sheet to dished structure form, subjection of the formed structure to two successive heats, the first heating in duration and temperature being insufficient to thermally effect the size and the like but sufficient for partially drying the formed non-flat structure to the desired degree, the second heating in duration and temperature being sufficient to "melt" and "flow" the size over the structure surface and to further dry the structure but insufficient to scorch the same, compacting by pressure the structure body size and the like between the heatings, and then ironing and consolidating the pulp body and "melted" surface following the second heating.

7. A method as defined by claim 3, characterized by pressure forming the free dried structure prior to thermal reaction drying.
